RAILWAY SIGNALING SYSTEM

Crawford E. Staples, Wilkinsburg, Pa., assignor to
 The Union Switch & Signal Company, Swiss-
 vale, Pa., a corporation of Pennsylvania

Application February 3, 1940, Serial No. 317,161

2 Claims. (Cl. 246—34)

My invention relates to a railway signaling system having track circuits employing coded or periodically interrupted current, and particularly to improved means for preventing improper operation of the system in the event an insulated joint separating two track sections becomes defective.

It has heretofore been proposed to provide means operable in the event an insulated joint separating two track sections is defective to establish a "lockout" circuit to supply steady uncoded energy to the section in the rear of the defective joint so that this energy will feed over the defective joint and maintain the track relay of the section in advance of the defective joint constantly energized to thereby cause the signal controlled by that track relay to display its most restrictive indication.

One means for accomplishing this result is shown in an application of Howard A. Thompson, filed May 28, 1938, Serial No. 210,743, for Railway traffic controlling apparatus, now U. S. Patent 2,213,420, granted Sept. 3, 1940. Another means for accomplishing this result is shown in an application of Ralph R. Kemmerer, filed June 30, 1939, Serial No. 282,185, for Railway signaling system, now U. S. Letters Patent 2,215,904, granted Sept. 24, 1940, while still another means for accomplishing this result is shown in an application of Leslie R. Allison and Frank H. Nicholson, filed February 24, 1940, Serial No. 320,654, for Railway signaling system, now U. S. Patent 2,235,134, granted Mar. 18, 1941.

It is an object of my invention to provide an improved railway signaling system incorporating a "lockout" circuit, the system being arranged so that it is non-cascading in operation, and being also arranged so that less equipment is required than is necessary in the systems heretofore known.

A further object of the invention is to provide a railway signaling system incorporating an improved non-cascading "lockout" circuit.

Other objects of my invention and features of novelty will be apparent from the following description taken in connection with the accompanying drawing.

I shall describe one form of railway signaling system embodying my invention and shall then point out the novel features thereof in claims.

In the drawing, the single figure is a diagram showing a railway signaling system embodying my invention.

Referring to the drawing, there is shown there-in a stretch of railway track having track rails

1 and 2 over which traffic normally moves in the direction indicated by the arrow, that is, from left to right. The rails of the track stretch are separated by insulated joints 3 into the customary successive track sections, and the rails of each of these sections form a part of a track circuit of the usual character.

The particular track stretch which is represented in the drawing is intended for use in a 10 railway system employing electric current for propulsion purposes, and for this reason alternating current track circuit energy is used together with impedance bonds 4 of the customary form which conduct the propulsion current around each pair of insulated rail joints. As the description proceeds, however, it will be apparent that the apparatus of this invention is equally well suited for use on a steam road in which the application of either direct or alternating current track circuit energy for control of the signals may be employed. In such an application the impedance bonds 4 would, of course, be omitted.

In the diagram comprising the drawing, one 25 complete track section, which is identified as section 12T, and parts of two other sections identified as sections 11T and 13T, are shown. Each of these track sections has located at the entrance end thereof a signal for governing movement of trains in the track stretch, the signal for section 12T being identified as 12S. The signal illustrated is of the familiar color light type having a green or proceed lamp G, a yellow or caution lamp Y, and a red or stop lamp R. It should be understood, however, that the invention is not restricted to the use of a signal of this type and that any appropriate kind of signal may be employed.

30 The rails of each track section form a part of a track circuit to which coded alternating current signal control energy is supplied at the exit or leaving end from the secondary of a track transformer designated TT with a prefix corresponding to that of the associated track section. The circuits for supplying current from the secondary windings of the track transformers include the usual current limiting reactors 6. The energy supplied to the track circuits is supplied from any suitable source, and may be distributed throughout the track stretch by a transmission line, not shown. In the drawing, the terminals BX and CX designate the terminals of 35 such power supply source, and it will be assumed that the energy supplied from the source is alter-

nating current with a frequency of 100 cycles per second.

Each of the signal locations has associated therewith a suitable source of direct current, such as a primary or storage battery, not shown, the terminals of which are designated in the drawing by the reference characters B and C.

The particular signaling system shown in the drawing is of the three indication variety, and it makes use of track circuit energy coded at two different frequencies. This coded energy is provided by code transmitters CT which interrupt the supply circuits of the associated track transformers a definite number of times a minute according to traffic or other conditions ahead. In the form shown, each code transmitter CT is provided with two circuit making and breaking contacts 75 and 180 which are continuously actuated by a motor or other suitable mechanism at two different speeds. For purposes of illustration it will be assumed that these speeds are such as to respectively provide 75 and 180 energy impulses per minute which are separated by periods of equal duration in which no energy is supplied.

Each of the track circuits includes a code following track relay designated TR together with an appropriate prefix. The track relay is located at the entrance end of the track section and may be of any suitable type. As shown, the relay is of the direct current type having its winding connected to the track rails of the associated track section through a suitable resonant unit RU shown diagrammatically in the drawing.

The resonant units RU each comprise a transformer, a capacitor and a reactor so arranged and proportioned as to freely pass the 100 cycle coded signal control energy, but so as not to pass propulsion current of a different frequency. Each resonant unit includes, in addition, a rectifier which converts into direct current the alternating current which is supplied through the unit.

The track relay 12TR has associated therewith auxiliary relays 12FSA, 12H and 12J, while each of the other signals in the track stretch has associated therewith equipment corresponding to that associated with signal 12S.

Referring to the drawing, contact 15 of the track relay 12TR controls the supply of current to the primary winding 20 of the decoding transformer 12DT, while contacts 16 and 17 control the supply of current to windings of relays 12FSA and 12H.

As shown in the drawing, contact 15 when released engages a contact which is connected to one end terminal of the transformer primary winding 20, while contact 15 when picked up engages a contact which is connected to the other end terminal of the winding 20. The center terminal of the winding 20 is connected to terminal C of the source of direct current, and, accordingly, when contact 15 of relay 12TR is picked up and released, the two end portions of the transformer primary winding 20 are alternately energized with the result that current is induced in the transformer secondary windings 21 and 22.

The contact 16 of track relay 12TR is connected to the center terminal of the transformer secondary winding 21, while one end terminal of the winding 21 is connected to one terminal of the pick-up winding 24 of relay 12FSA. The other terminal of the winding 24 is connected to a contact which is engaged by track relay con-

tact 16 when contact 16 is in its released position.

Contact 16 when picked up engages a contact which is connected to contact 25 of relay 12FSA, 5 while contact 25 when picked up engages a contact which is connected to one terminal of the winding of relay 12H, the other terminal of which is connected to an end terminal of the transformer secondary winding 21.

- 10 The relay 12FSA has a holding winding 27 one terminal of which is constantly connected to terminal C of the source of current, while the other terminal of the winding 27 is connected to contact 28 of relay 12FSA. Contact 28 when picked up engages a contact which is connected to contact 28 of relay 12H, while contact 29 when released engages a contact which is connected to a contact which is engaged by track relay contact 17 when contact 17 is picked up.
- 15 The secondary winding 22 of decoding transformer 12DT is connected to the resonant unit 12RUA from which current is supplied to the winding of the relay 12J. The resonant unit 12RUA is similar in construction to the unit 25 12RU, and the elements of the unit are arranged and proportioned so that the unit will transmit sufficient current to the winding of relay 12J to maintain the contact of relay 12J picked up when the frequency of the current induced in 30 the transformer secondary winding 22 is that which is present when the track relay 12TR is responding to energy of the 180 code frequency. The unit 12RUA is also arranged and proportioned so that when the track relay 12TR is responding to energy of any other code frequency, such as 75 code frequency, insufficient energy is supplied to the winding of relay 12J to maintain the contact of that relay picked up.

- 35 The relay 12H is of a type the contacts of which 40 are slow in releasing with the result that the relay contacts when picked up remain picked up during the intervals between the supply of impulses of energy to the relay winding, while the contacts also remain picked up during momentary interruptions in the supply of impulses of energy to the relay winding, such as occur when the code supplied to the track relay is changed from one frequency to another. In addition, the contacts of relay 12H when picked up 45 remain picked up until after the contacts of relay 12FSA become released when the supply of energy to the windings of these relays is discontinued as a result of cessation of code following operation of the track relay.

- 50 The relay 12H and the transformer 12DT are selected and proportioned so that the contacts of the relay, when released, will not become picked up on the supply of one impulse of energy from the transformer secondary winding 21 to 55 the relay winding, but will become picked up on the supply of two or more of these impulses in rapid succession, such as occur when code following operation of the track relay is initiated.

- The auxiliary relays 12FSA and 12H cooperate 60 to control the supply of energy to the primary winding 32 of track transformer 11TT, and to also control the circuits of the lamps of signal 12S in the manner hereinbefore explained in detail.

- 65 The equipment is shown in the drawing in the condition which it assumes when the track sections 12T and 13T are vacant, at which time the equipment associated with section 13T operates in the manner hereinafter described in detail in connection with section 12T to supply en-
- 70 75

ergy of the 180 code frequency to the track transformer 12TT, while this energy feeds to the track relay 12TR to produce code following operation of the contacts thereof.

As a result of movement of the track relay contact 15 between its released and picked-up positions, the end portions of the transformer primary winding 20 are alternately energized and current is induced in the secondary windings 21 and 22 of the transformer 12DT.

On each movement of the track relay contact 16 to its released position, the circuit is established to supply an impulse of energy from the left-hand end portion of the transformer secondary winding 21 to the winding 24 of relay 12FSA. This circuit is traced from the center terminal of the transformer secondary winding 21 through back contact 16 of track relay 12TR, and winding 24 of relay 12FSA to the left-hand end terminal of the secondary winding 21.

As a result of the supply of impulses of energy to the winding 24 of relay 12FSA, the contacts of this relay are maintained picked up and contact 25 establishes the circuit for supplying energy to the winding of relay 12H when the track relay contacts are in their picked-up position. Accordingly, when contact 16 engages its front contact energy is supplied to the winding of relay 12H from the right-hand end portion of the transformer secondary winding 21 over the circuit which is traced from the center terminal of the transformer winding 21 through front contact 16 of track relay 12TR, front contact 25 of relay 12FSA, and winding of relay 12H to an end terminal of the winding 21.

As a result of the supply of impulses of energy to the winding of relay 12H, the contacts of this relay are maintained picked up and contact 29 interrupts the circuit of the holding winding 27 of relay 12FSA with the result that engagement of contact 17 of the track relay 12TR with its front contact does not affect the supply of energy to the winding 27 of relay 12FSA.

Since the contacts of the track relay 12TR are responding to energy of the 180 code frequency, the frequency of the current induced in secondary winding 22 of transformer 12DT is such that it is freely passed by the resonant unit 12RUA, and this unit supplies sufficient current to the winding of relay 12J to maintain the contact of that relay picked up.

As contact 34 of relay 12H is picked up and as contact 35 of relay 12J is also picked up, the circuit for supplying energy to the green or proceed lamp G of signal 12S is complete, and is traced from terminal B of the source of current through front contact 34 of relay 12H, and front contact 35 of relay 12J to one terminal of the lamp G, the other terminal of which is connected to terminal C of the source of current.

At this time, as the contacts of relays 12FSA and 12H are picked up, the circuit for supplying energy of the 180 code frequency to the track transformer 11TT is complete, and is traced from terminal BX of the source of signal current through front contact 36 of relay 12H, contact 180 of code transmitter 12CT, and front contact 38 of relay 12FSA to one terminal of the transformer primary winding 39, the other terminal of which is connected to terminal CX of the source of signal control energy.

Operation of the equipment on movement of a train in the normal direction of traffic

When a train moving in the normal direction

of traffic enters section 12T it shunts the track relay 12TR with the result that the contacts of this relay thereafter remain in their released position, and energy is not induced in the secondary windings 21 and 22 of transformer 12DT, while contact 17 of the track relay interrupts the circuit through which energy is at times supplied to the holding winding 27 of relay 12FSA.

As energy is no longer induced in secondary winding 21, impulses of energy are no longer supplied to the winding 24 of relay 12FSA, and as contact 16 of track relay 12TR is in its released position the circuit of the winding of relay 12H is interrupted. As a result the contacts of the relays 12FSA and 12H become released. At this time as contact 17 of the track relay 12TR is released, the circuit of the holding winding 27 of relay 12FSA is interrupted and cannot be established during release of the contacts of relays 12FSA and 12H.

In addition, as current is not induced in secondary winding 22 of transformer 12DT, energy is no longer supplied to the winding of relay 12J, and the contact of that relay becomes released.

On release of contact 38 of relay 12FSA, the circuit for supplying energy of the 180 code frequency to the track transformer 11TT is interrupted, while on release of contact 36 of relay 12H the circuit for supplying energy of the 75 code frequency to the track transformer 11TT is established. This circuit is traced from terminal BX of the source of signal control current through back contact 36 of relay 12H, contact 15 of code transmitter 12CT, and back contact 40 of relay 12FSA to one terminal of the winding 39 of transformer 11TT, the other terminal of which is connected to terminal CX of the source of signal control current.

In addition, on release of the contacts of relay 12H, contact 34 interrupts the previously traced circuit for illuminating the green lamp G, and establishes the circuit to illuminate the red or stop lamp R of signal 12S. This circuit is traced from terminal B of the source of current through back contact 34 of relay 12H to one terminal of the red lamp R, the other terminal of which is connected to terminal C of the source of current.

As the train proceeds through the track stretch and enters section 13T, the track relay for that section is shunted and the equipment associated therewith operates in the manner described in detail in connection with section 12T to condition the signal for section 13T to display its red or stop indication, while the energy supplied to the rails of section 12T is changed from 180 code frequency to 75 code frequency.

As long as any portion of the train remains in section 12T, the track relay 12TR continues to be shunted, but when the rear of the train vacates section 12T, the impulses of energy supplied by track transformer 12TT to the track rails of section 12T feed to the track relay 12TR and produce code following operation of the contacts thereof.

On initial movement of the track relay contact 15 from the released to the picked-up position there is a change in energization of the primary winding 20 of transformer 12DT, and an impulse of energy is induced in secondary winding 21. At this time, however, since contact 16 of the track relay is in its picked-up position, the circuit of the winding 24 of relay 12FSA is interrupted, while as contact 25 of re-

lay 12FSA is released the circuit of the winding of relay 12H is interrupted. Accordingly, energy is not supplied from secondary winding 21 of transformer 12DT to the winding of either of the relays 12FSA and 12H on the first picked-up period of the track relay contacts.

In addition, at this time, as contact 28 of relay 12FSA is released the circuit of the holding winding 27 of the relay is interrupted, and energy is not supplied to this winding at this time.

On movement of the track relay contacts to their released position following their initial movement to the picked-up position, there is another change in energization of the primary winding 29 of transformer 12DT, and another impulse of energy is induced in secondary winding 21. At this time, as contact 16 of the track relay is in its released position, the circuit for supplying energy from the transformer secondary winding 21 to the winding 24 of relay 12FSA is complete, and hence an impulse of energy is supplied to the winding 24 of relay 12FSA and the relay contacts become picked up.

On picking up of the contacts of relay 12FSA contact 43 interrupts the circuit for supplying energy of the 75 code frequency to the track transformer 11TT, and establishes the "lockout" circuit for supplying steady uncoded energy to the transformer 11TT. This circuit is traced from terminal BX of the source of signal control current through back contact 36 of relay 12H, and front contact 40 of relay 12FSA to primary winding 39 of transformer 11TT.

As a result of picking up of the contacts of relay 12FSA contact 25 establishes the circuit of the winding of relay 12H so that on the next or second picked-up period of the track relay contacts an impulse of energy is supplied from the transformer secondary winding 21 to the winding of relay 12H. However, as explained above, the contacts of the relay 12H do not become picked up on the supply of the first impulse of energy to the relay winding, and the contacts of relay 12H remain released at this time.

At this time as the contacts of relay 12FSA are picked up and the contacts of relay 12H are released, an impulse of energy is supplied to the holding winding 27 of relay 12FSA over the circuit which is traced from terminal B of the source of direct current through front contact 17 of track relay 12TR, back contact 29 of relay 12H, front contact 28 of relay 12FSA, and winding 27 to terminal C of the source of current. Energization of the holding winding 27 at this time aids in maintaining the contacts of the relay 12FSA picked up and assures that the "lock-out" circuit will be maintained until it is interrupted by picking up of the contacts of relay 12H.

On the next or second released period of the track relay contacts another impulse of energy is supplied to the winding 24 of relay 12FSA, and the contacts of this relay are maintained picked up so that on the next or third picked-up period of the track relay contacts another impulse of energy is supplied to the winding of relay 12H.

At the time the second impulse of energy is supplied to the winding of relay 12H, the flux developed in the relay core as a result of the supply of the first impulse of energy to the relay winding will not have completely died out, and the second impulse of energy supplied to the relay winding will cause the flux in the relay core to build up to a value high enough to cause the relay contacts to become picked up.

On picking up of the contacts of relay 12H, contact 29 interrupts the previously traced circuit for supplying energy to the holding winding 27 of relay 12FSA, while contact 36 of relay 12H interrupts the previously traced "lockout" or steady energy supply circuit for supplying steady energy to the track transformer 11TT.

On picking up of contact 36 of relay 12H, the circuit for supplying energy of the 180 code frequency to the track transformer 11TT is complete, and is traced from terminal BX of the source of signal control current through front contact 36 of relay 12H, contact 180 of code transmitter 12CT, and front contact 38 of relay 12FSA to one terminal of the primary winding 39, the other terminal of which is connected to terminal CX of the source of signal control current.

At this time as the track relay 12TR is responding to energy of the 75 code frequency, the frequency of the current induced in the secondary winding 22 of transformer 12DT is such that it is not freely passed by the resonant unit 12RUA, and too little current is supplied to the winding of relay 12J to pick up the contact of this relay. Accordingly, on picking up of the contact 34 of relay 12H the circuit of the red lamp R is interrupted, and the circuit for lighting the yellow lamp Y is established, and is traced from terminal B of the source of current through front contact 34 of relay 12H, back contact 35 of relay 12J, and lamp Y to terminal C of the source of current.

When the train has advanced far enough in the track stretch to vacate section 13T, the equipment associated therewith operates in the manner described in detail in connection with the equipment associated with section 12T to supply energy of the 180 code frequency to the transformer 12TT. On this change in the frequency of the energy supplied to the rails of section 12T, and thus to the track relay 12TR, the track relay contacts operate at a higher speed, and the windings of the relays 12FSA and 12H are maintained energized, while the resonant unit 12RUA supplies sufficient energy to the winding of relay 12J to pick up the contact of this relay.

On picking up of contact 35 of relay 12J, the circuit of the yellow lamp Y is interrupted, while the circuit of the green lamp G is established, and is traced from terminal B of the source of current through front contact 34 of relay 12H, front contact 35 of relay 12J, and lamp G to terminal C of the source of current.

On this change in the rate of operation of the track relay contacts, the windings of relays 12FSA and 12H are maintained energized, and the contacts of these relays are maintained picked up, and maintain the circuit for supplying energy of the 180 code frequency to the track transformer 11TT.

Operation of equipment in the event an insulated joint breaks down as a result of passage of a train

For purposes of illustration it will be assumed that the track stretch is vacant so that energy of the 180 code frequency is supplied to the rails of section 12T, that a train moving in the normal direction of traffic passes through the track stretch, and that an insulated joint 3 separating sections 11T and 12T breaks down as a result of passage of a train.

In electrified territory because of the well-known operation of the impedance bonds 4, breaking down of one insulated joint has the same effect as breaking down of both insulated joints in steam propulsion territory, and permits the impulses of current supplied to the section in the rear of the defective joint to feed to the track relay of the section in advance of the defective joint.

When the train under consideration enters the section 12T it shunts the track relay 12TR and the equipment associated therewith operates in the manner heretofore explained in detail to condition the signal 12S to display its red or stop indication, while energy of the 75 code frequency is supplied to the track transformer 11TT.

When the train advances in the track stretch far enough for the rear end thereof to be located in advance of the track relay 12TR, the impulses of energy supplied to the rails of section 11T feed over the defective insulated joint 3 to the winding of relay 12TR, but because of the shunting action of the wheels and axles of vehicles forming the train too little current is supplied to the winding of the track relay 12TR to pick up the contacts thereof until the train has advanced some distance beyond the point of connection of the winding of relay 12TR with the track rails of the section 12T. When the train has advanced this far sufficient energy will be supplied to the winding of relay 12TR as a result of the impulses of energy feeding over the defective joint 3 to pick up the contacts of relay 12TR and code following operation of the relay contacts will result.

On the first movement of the track relay contacts to their picked-up position, there is a change in the energization of primary winding 20 of transformer 12DT, as explained above, so that impulses of energy are induced in the secondary windings 21 and 22. At this time, however, energy is not supplied to the winding of relay 12H since contact 25 of relay 12FSA is released, while the circuit of the winding 24 of relay 12FSA is not complete since contact 16 of track relay 12TR is picked up.

Accordingly, on this first movement of the track relay contacts to their picked-up position, the contacts of the relays 12FSA and 12H remain released.

On the first "off" period following the first "on" period in the code feeding over the defective joint, the contacts of the track relay 12TR become released and there is another change in the energization of transformer primary winding 20 so that another impulse of energy is induced in the secondary windings 21 and 22. On release of the track relay contacts, contact 16 completes the previously traced circuit for supplying an impulse of energy from the secondary winding 21 to the winding 24 of relay 12FSA and the contacts of relay 12FSA become picked up.

As a result of picking up of the contacts of relay 12FSA, contact 40 interrupts the circuit for supplying energy of the 75 code frequency to the track transformer 11TT, and establishes the steady energy or "lockout" circuit for supplying steady uncoded energy to the transformer 11TT.

In addition, as a result of the picking up of the contacts of relay 12FSA, contact 23 partially establishes the circuit for supplying energy to the holding winding 27 of relay 12FSA, this circuit being completed on subsequent picking up of the track relay contact 17, while contact 38 of relay

12FSA establishes the circuit for supplying energy to the winding of relay 12H.

As the result of the supply of steady energy to the transformer 11TT through the steady energy or "lockout" circuit, energy feeding over the defective joint picks up the contacts of track relay 12TR, and another impulse of energy is induced in secondary windings 21 and 22 of transformer 12DT. In addition, as a result of the picking up of the track relay contacts, contact 17 completes the circuit for supplying energy to the holding winding 27 of relay 12FSA, this circuit being complete at this time since contact 29 of relay 12H is released and contact 28 of relay 12FSA is picked up.

On picking up of the track relay contacts, contact 16 establishes the circuit for supplying energy from the transformer secondary winding 21 to the winding of relay 12H and an impulse of energy is supplied to the winding of relay 12H. However, as pointed out above, the relay 12H and the transformer 12DT are selected and proportioned so that the contacts of this relay do not become picked up on the supply of one impulse of energy to the relay winding, and hence the contacts of this relay remain released, and contact 29 maintains the circuit for supplying energy to the holding winding 27 of relay 12FSA, while contact 36 of relay 12H maintains the steady energy or "lockout" circuit for supplying steady uncoded energy to the track transformer 11TT.

As the "lockout" circuit for supplying steady energy to the track transformer 11TT is maintained, steady energy feeds over the defective joint and holds the contacts of the track relay 12TR constantly picked up with the result that there are no further changes in energization of the primary winding 20 of transformer 12DT. Accordingly, no further impulses of energy are induced in secondary windings 21 and 22, and energy is not supplied to the winding of relay 12H even though contact 25 of relay 12FSA and contact 16 of track relay 12TR are both picked up. The contacts of relay 12H therefore remain released and contact 36 maintains the "lockout" circuit, while contact 29 maintains the circuit of the holding winding 27 of relay 12FSA, and contact 34 maintains the circuit of the red or stop lamp R of signal 12S.

As a result of the supply of steady energy to the transformer 11TT, the contacts of the track relay for section 11T are maintained constantly picked up, and the signal for that section is conditioned to display its red or stop indication, but as hereinafter explained in detail, the equipment associated with the track relay for section 11T will operate to supply energy of the 75 code frequency to the adjacent section in the rear.

Operation of the equipment if an insulated joint breaks down when the stretch is vacant

For purposes of illustration it will be assumed that an insulated joint 3 separating sections 11T and 12T breaks down at a time when the track stretch is vacant, at which time energy of the 180 code frequency is supplied to the rails of section 12T.

As the relay 12TR is assumed to be responding to energy of the 180 code frequency, the contacts of all of the auxiliary relays associated with relay 12TR are picked up, and energy of the 180 code frequency is supplied to the rails of section 11T, while the signal 12S is conditioned to display its green or proceed indication.

If at the time the insulated joint separating

sections 11T and 12T breaks down the impulses of energy supplied to section 11T are out of step with those supplied to the rails of section 12T, the impulses of energy supplied to the rails of section 11T, and feeding over the defective insulated joint to the relay 12TR, will fill in the "off" periods in the code supplied to the section 12T, with the result that the contacts of the relay 12TR will be maintained picked up all or substantially all of the time.

If at the time the insulated joint separating sections 11T and 12T breaks down the impulses of coded energy supplied to the rails of section 11T are substantially in step with those supplied to the rails of section 12T, they will soon become out of step. This will be true because the codes for the two sections are generated by different code transmitters and these code transmitters are operated by separate motors. These motors will not operate at exactly the same speed, and if at the time the joint breaks down the impulses of code are in step, they will soon become out of step because of the difference in the speed of the motors driving the code transmitters. When the impulses of code become out of step, there will be an increase in the duration of the picked-up periods of the track relay contacts due to the increase in the portion of the total time during which energy is supplied to the relay winding.

In consequence of the lengthened picked-up periods of the contacts of the track relay 12TR, the contact 16 of track relay 12TR will not engage its back contact, or will engage it for such short time intervals, that energization of the winding 24 of relay 12FSA is reduced below the value effective to maintain the relay contacts picked up.

On release of the contacts of relay 12FSA, contact 38 interrupts the circuit for supplying energy of the 180 code frequency to the track transformer 11TT, and establishes a circuit to supply steady energy to the transformer 11TT. This circuit is traced from terminal BX of the source of signal control current through front contact 36 of relay 12H, and back contact 38 of relay 12FSA to one terminal of the primary winding 39 of transformer 11TT.

On the supply of steady energy to the transformer 11TT, steady energy is supplied to the rails of section 11T and feeds over the defective joint to the track relay 12TR and maintains the track relay contacts constantly picked up.

As the contacts of track relay 12TR are picked up all or substantially all of the time by the scrambled code supplied thereto prior to the release of the contacts of relay 12FSA, and are constantly picked up by the steady energy supplied to the relay winding after the release of the contacts of relay 12FSA, little or no change occurs in the energization of the primary winding 20 of transformer 12DT, and hence very weak impulses of energy or none at all are induced in secondary winding 21. Accordingly, even though contact 16 of the track relay 12TR is picked up to establish the circuit for supplying energy from the winding 21 to the winding of relay 12H, no current or very weak impulses of current are supplied to the winding of relay 12H, and after a time interval the contacts of the relay 12H become released.

It is to be observed that the contacts of the relay 12H remain picked up until after the contacts of the relay 12FSA become released because 75

of the slow release characteristic of the relay 12H.

On the release of the contacts of relay 12H, contact 34 interrupts the circuit of the green lamp G, and establishes a circuit for illuminating the red or stop lamp R.

In addition, on release of the contacts of relay 12H, contact 36 interrupts the previously traced circuit for supplying steady energy to the track 10 transformer 11TT, and engages its back contact to complete the circuit for supplying energy of the 75 code frequency to the transformer 11TT.

On the supply of energy of the 75 code frequency to the transformer 11TT, energy of this 15 frequency is supplied to the track rails of section 11T, and feeds over the defective joint where it combines with the energy of 180 code frequency supplied by track transformer 12TT.

As a result of the supply of energy of the two 20 code frequencies to the track relay 12TR, the relay contacts are picked up most of the time, but a time will quickly be reached when the relationship of the two codes is such that the contacts of the track relay will become released, thereby producing a change in the energization of primary winding 20 of transformer 12DT with the result that an impulse of energy is induced in secondary winding 21. In addition, on release of the track relay contacts, contact 16 25 establishes the circuit for supplying energy from the secondary winding 21 to the winding 24 of relay 12FSA, and the contacts of relay 12FSA become picked up.

As a result of picking up of the contacts of 30 track relay 12FSA, contact 40 interrupts the circuit for supplying energy of the 75 code frequency to the track transformer 11TT, and establishes the "lockout" or steady energy supply circuit for supplying steady uncoded energy to the transformer 11TT. This steady energy will feed over the defective joint to the track relay 12TR and cause the track relay contacts to again become picked up, while on picking up of the contacts of the track relay 12TR, contact 17 35 completes the circuit for supplying energy to the holding winding 27 of relay 12FSA. This circuit is complete at this time since the contacts of relay 12H are released and the contacts of relay 12FSA are picked up, while on the supply of energy to the holding winding 27, the contacts of relay 12FSA are thereafter constantly picked up to maintain the steady energy or "lock-out" circuit.

In addition, on the supply of steady energy 55 to the track relay 12TR, the relay contacts are constantly picked up so that there is thereafter no further change in the energization of primary winding 20 of relay 12DT.

On the movement of the track relay contacts 60 to their picked-up position as the result of the supply of steady energy over the "lockout" circuit, there is a change in the energization of primary winding 20 and energy is induced in the secondary winding, while contact 16 of the track relay establishes the circuit for supplying 65 an impulse of energy to the winding of relay 12H. However, as previously pointed out, the characteristics of the relay 12H are such that the relay contacts when released will not become picked up on the supply of a single impulse of energy to the relay winding, and hence the relay contacts remain released at this time and maintain the "lockout" or steady energy circuit, and also maintain the circuit for supplying energy to the holding winding 27 of relay 12FSA.

Operation of the equipment when steady energy is supplied to a track relay by means other than the lockout circuit controlled by that relay

The system provided by this invention is arranged so that if steady energy is supplied to a track relay by any means other than the "lockout" circuit controlled by that relay, the equipment associated with the track relay to which the steady energy is supplied will not repeat the supply of steady energy to the adjacent section in the rear. This non-cascading feature of the system provided by this invention makes it unnecessary to employ special cut section facilities to prevent cascading of steady energy, while it also makes it possible to employ steady energy to discontinue operation of highway traffic signals or for other purposes.

For purposes of illustration it will be assumed that an insulated joint 3 separating sections 12T and 13T breaks down as a result of passage of a train, and that the equipment associated with section 13T operates in the manner described in detail in connection with section 12T to first supply energy of 75 code frequency to the rails of section 12T, and to thereafter establish the "lockout" circuit controlled thereby to supply steady energy to the rails of section 12T.

As explained above, when any part of the train is present in section 12T, the track relay 12TR is shunted, while when the train enters section 13T the track relay for that section is shunted and the equipment controlled thereby operates to supply energy of the 75 code frequency to the track transformer 12TT.

As soon as the train vacates section 12T, the energy of 75 code frequency supplied to the transformer 12TT, and by it to the rails of section 12T, will feed to the track relay 12TR and effect code following operation of the contacts thereof.

At this time impulses of energy of the 75 code frequency supplied to the rails of section 12T will also feed over the defective joint to the rails of section 13T, but a short time interval will elapse before the train will have advanced far enough in the track stretch for the energy feeding over the defective insulated joint to effect operation of the track relay for section 13T to establish the "lockout" circuit to supply steady uncoded energy to the rails of section 12T, and, accordingly, the track relay 12TR will respond to energy of the 75 pulse frequency during this time interval.

On the supply of coded energy to the track relay 12TR, the contacts of the relay 12FSA become picked up on the first released period of the track relay contacts, as explained above, while the contacts of the relay 12H become picked up on the third picked-up period of the track relay contacts. When the contacts of the relays 12FSA and 12H are picked up, the circuit for supplying the energy of 180 code frequency to the track transformer 11TT is complete, while the circuit for illuminating the yellow or caution lamp Y of signal 12S is established.

When the train has advanced some distance in section 13T the impulses of energy feeding over the defective joint from section 12T cause operation of the track relay for section 13T to establish the "lockout" circuit so that steady uncoded energy is supplied to the rails of section 12T. This energy feeds to the track relay 12TR and maintains the relay contacts constantly picked up.

When the contacts of track relay 12TR are constantly picked up, the circuit of the winding 24 of relay 12FSA is interrupted, while thereafter no changes occur in energization of the transformer

6 primary winding 20, so that energy is not supplied from the transformer secondary winding 21 to the winding of relay 12H. Accordingly, the contacts of the relays 12FSA and 12H become released.

10 However, because of the slow release characteristic of the relay 12H, the contacts of this relay remain picked up until after the contacts of the relay 12FSA become released. This eliminates all possibility that energy will be supplied to the

15 holding winding 27 of relay 12FSA at this time, since contact 28 of relay 12FSA interrupts the circuit of the holding winding before contact 29 of relay 12H becomes released to establish the circuit.

20 As the holding winding 27 of relay 12FSA is not energized, the contacts of relay 12FSA become released and remain released, and as the contacts of relay 12H are also released, the circuit for supplying energy of the 75 code frequency to the track transformer 11TT is established, while contact 34 of relay 12H establishes the circuit for illuminating the red or stop lamp R of signal 12S.

From the foregoing it will be seen that when an insulated joint separating two track sections

30 breaks down as a result of passage of a train, and the equipment associated with the section in advance of the joint operates to establish the "lockout" circuit to supply steady energy to the section in the rear of the defective joint, that

35 the equipment associated with the track relay of the section in the rear of the defective joint will be conditioned to cause the signal for that section to display its stop indication, and that the supply of steady energy to the section further in the rear will not be repeated, but on the contrary, coded energy will be supplied to such section further in the rear.

The system provided by this invention is adapted for use in track stretches which include intersections with highways since this system makes

45 it possible to employ steady energy to discontinue operation of a highway crossing signal without interfering with operation of the signals controlling movement of trains through the track stretch.

50 The system provided by this invention is arranged so that when steady energy is supplied to a track relay by any means other than the "lockout" circuit controlled by the track relay of the

55 adjacent section in advance, or by the track relay to which the steady energy is supplied, the signal controlled by the track relay to which the steady energy is supplied will be conditioned to display its stop indication, while energy of the 75 code frequency will be supplied to the rails of the adjacent section in the rear.

60 Steady energy may be supplied to a track relay where back contact coding is employed at a cut section in a track circuit. Such a cut section may be required because of the length of a signal block, or it may be installed to aid in the control of a highway crossing signal. One form of apparatus for providing back contact coding at a cut section is shown in an application of Charles

65 B. Shields and Herman G. Blosser, Serial No. 275,146, filed May 23, 1939, for Railway traffic controlling apparatus, now U. S. Letters Patent 2,211,174, granted Aug. 13, 1940.

70 Likewise, steady energy may be employed in a track circuit to control a highway crossing sig-

nal, as explained in the application of R. R. Kemmerer identified above.

For purposes of illustration it will be assumed that the section 12T is divided into two parts, that back contact coding equipment is located at the cut section, and that the equipment at the cut section operates when the forward portion of the track section is unoccupied to repeat to the rearward portion of the track section energy of the same code frequency as is supplied to the rails of the forward portion of the track section. The cut section facilities also operate when the forward portion of the track section is occupied to supply steady uncoded energy to the rails of the rearward portion of the section.

On passage of a train through the track stretch, on entrance of the train into section 12T the track relay 12TR is shunted, and the contacts of the relays 12FSA and 12H are released, while the equipment operates as described above to supply energy of the 75 code frequency to the rails of section 12T, and to condition the signal 12S to display its red or stop indication.

When the train enters the forward portion of section 12T the equipment at the cut section operates in the usual manner to discontinue the supply of coded energy to the rearward portion of the track section and to supply steady energy thereto.

As long as any portion of the train remains in the rearward portion of the track section, the track relay 12TR is shunted and its contacts remain released. As soon as the train vacates the rearward portion of the track section, the steady energy which is supplied to the rails thereof by the cut section apparatus feeds to the track relay and causes the relay contacts to become picked up and remain picked up.

On picking up of the track relay contacts an impulse of energy is induced in secondary winding 21 of the decoding transformer, but at this time contact 16 does not establish the circuit of the winding 24 of relay 12FSA so that the contacts of relay 12FSA remain released, and, as contact 25 of relay 12FSA is released, the circuit of the winding of relay 12H is incomplete and the contacts of this relay remain released.

It will be seen, therefore, that on the supply of steady energy to the track relay 12TR under the conditions outlined, the contacts of the relays 12FSA and 12H remain released, and thereby maintain the circuit for supplying energy of the 75 code frequency to the rails of section 12T, while contact 34 of relay 12H maintains the circuit of the red or stop lamp R of signal 12S.

As the train proceeds through the track stretch and enters the section in advance of the forward portion of the section 12T, the track relay for that section in advance is shunted and energy of the 75 code frequency is supplied to the rails of the forward portion of 12T so that when the train vacates the forward portion of section 12T, the cut section facilities operate in the usual manner to repeat the supply of energy of the 75 code frequency to the rails of the rearward portion of section 12T.

As a result of the supply of coded energy to the track relay 12TR, the contacts of this relay become released to thereby supply an impulse of energy to the winding 21 of relay 12FSA, and on continued code following operation of the track relay contacts energy is supplied to the winding of relay 12H. Accordingly, the contacts of the relays 12FSA and 12H become picked up in the manner heretofore described in detail so that the

signal 12S is conditioned to display its yellow or caution indication, while energy of the 180 code frequency is supplied to the track transformer 11TT.

5 Although I have herein shown and described only one form of railway signaling apparatus embodying my invention, it is understood that various changes and modifications may be made therein within the scope of the appended claims 10 without departing from the spirit and scope of my invention.

Having thus described my invention, what I claim is:

1. In a coded railway signaling system, in 15 combination, a stretch of railway track having a pair of track rails divided by insulated joints into successive track sections including adjoining forward and rearward sections, means for at times supplying coded energy and at other times supplying steady energy to the rails of said forward section, a code following track relay having a winding receiving energy from the rails of said forward section, a transformer, a first and a second auxiliary relay associated with said track relay, means including a contact of said track relay for varying the energization of the transformer primary winding in response to code following operation of the track relay, means operative when the track relay contacts are in their 20 released position for supplying energy from the transformer secondary winding to a winding of the first auxiliary relay, a holding circuit operative when the contacts of the track relay and of the first auxiliary relay are picked up for supplying energy to a winding of the auxiliary relay to maintain the contacts of the auxiliary relay picked up, means responsive to continued code following operation of the track relay subsequent to picking up of the contacts of the first auxiliary relay for supplying energy to the winding of the second auxiliary relay, a first supply circuit for supplying coded energy to the rails of said rearward section, said first supply circuit including a back contact of one of said auxiliary 25 relays, a second supply circuit for supplying steady energy to the rails of said rearward section, said second supply circuit being complete when and only when the contacts of the first auxiliary relay are picked up and the contacts of the second auxiliary relay are released, and a third supply circuit established on picking up of the contacts of the second auxiliary relay for supplying coded energy to the rails of said rearward section.

55 2. In a coded railway signaling system, in combination, a stretch of railway track having a pair of track rails divided by insulated joints into successive track sections including adjoining forward and rearward sections, means for at times 60 supplying coded energy and at other times supplying steady energy to the rails of said forward section, a code following track relay having a winding receiving energy from the rails of said forward section, a transformer, a first and a second auxiliary relay associated with said track relay, means including a contact of said track relay for varying the energization of the transformer primary winding in response to code following operation of the track relay, means operative 65 when the track relay contacts are in their released position for supplying energy from the transformer secondary winding to a winding of the first auxiliary relay, a holding circuit including front contacts of the track relay and of the first auxiliary relay and a back contact of

the second auxiliary relay for supplying energy to a winding of the first auxiliary relay to maintain the contacts of said relay picked up, a circuit including front contacts of the track relay and the first auxiliary relay for supplying energy from the transformer secondary winding to the winding of the second auxiliary relay, the transformer and the second auxiliary relay being proportioned so that the relay contacts when released become picked up only after a plurality of impulses of energy have been supplied from the transformer to the relay winding, a first supply circuit for supplying coded energy to the rails

5 of said rearward section, said first supply circuit including a back contact of one of said auxiliary relays, a second supply circuit for supplying steady energy to the rails of said rearward section, said second supply circuit being complete when and only when the contacts of the first auxiliary relay are picked up and the contacts of the second auxiliary relay are released, and a third supply circuit established on picking up of the contacts of the second auxiliary relay for supplying coded energy to the rails of said rearward section.

10 CRAWFORD E. STAPLES.
